C. R. BOWERS

ROLLING TOOL AND HOLDING DEVICE

Filed March 6, 1923

INVENTOR.

CHARLES R. BOWERS.

BY

Charles R. Bowers

ATTORNEYS.

UNITED STATES PATENT OFFICE.

CHARLES R. BOWERS, OF FRANKFORT, INDIANA.

ROLLING TOOL AND HOLDING DEVICE. .

Application filed March 6, 1923. Serial No. 623,079.

To all whom it may concern:

Be it known that I, CHARLES R. BOWERS, a citizen of the United States, and a resident of Frankfort, county of Clinton, and State of Indiana, have invented a certain new and useful Rolling Tool and Holding Device; and I do hereby declare that the following is a full, clear, and exact description thereof, reference being had to the accompanying drawings, in which like numerals refer to like parts.

This invention relates to a repair tool for attaching a connecting key to a shaft by the usual beading or rolling operation.

The main object of the invention is to provide a small hand-operated device for rolling the periphery of the metal connecting key and forcing it into an annular groove in the shaft to which it is to be secured, the device being small and simple in construction so as to be available to the small garage and machine shop.

One feature of the invention resides in the method of supporting the attaching key and shaft in position to be operated upon; and another feature thereof resides in the means for adjustably clamping and securing the same in a suitable vise or holder so as to permit the key to be rolled at a given distance from its end.

Still another feature of the invention resides in the beading tool and its construction, whereby the engaging rollers thereof will roll the bead upon the rotation of the tool, the pressure applied thereby being neutralized by the relative positions of the rollers.

The full nature of the invention will be understood from the accompanying drawings and the following description and claims.

In the drawings, Figure 1 is a plan view looking down on the tool and holder therefor, with the shaft removed. Fig. 2 is a side elevation showing the tool applied to the shaft in operative position. Fig. 3 is a central vertical section through the shaft, and a portion of the holder and tool.

In the drawings there is shown a holding socket 10 which is annular and cup-shaped mounted upon the base 11. On the opposite end of the base 11, there is another holder 12 of suitable diameter for supporting and securing the movable pinion mounted on the shaft, which, however, does not form a part of this invention. Secured within the

socket or holder 11, and loosely mounted therein, there is a receiving member 13 provided with a central bore or recess for receiving the bifurcated or key end of the connecting key 14. Rigidly secured in the body of the member 13, there is an upwardly extending pin 15 positioned to extend between the bifurcated ends of the key 14 for preventing its turning therein. For locking the member 13 rigidly in the socket 10, there is a set screw 16.

The shaft 17 which is hollow and provided with external screw threads upon which the pinion 18 is mounted, is provided with a head or enlarged portion 19 which is formed integral therewith. Said head 19 is provided with a reduced portion 20 in which is formed an annular groove 21 to receive the bead 22 which may be rolled therein by the tool hereinafter to be described. Rigidly secured at the opposite end of the shaft from the head 19, there is a collar 23, all of which construction forms a part of a starter shaft for starting an internal combustion engine through the medium of an electric motor in the usual manner. For adjustably clamping the shaft in position, there is provided a rod 24 having a head 25 keyed to one end thereof, said head being provided with the wings 26 for enabling it to be readily grasped and turned. Said shaft is adapted to extend through the hollow shaft 17 in the collar 19 and is provided with screw threads on the opposite end adapted to screw through an internally threaded central opening in the member 13, whereby the end thereof will engage the bottom of the socket 10. Mounted adjacent the head 25, there is a wing nut 38 arranged to screw about the upper threaded portion of the rod and contact with the top of the collar 23. For mounting the shaft and connecting key in position to be operated upon and properly adjusting the same, the key 14 may be first mounted in position within the member 13 so that it is engaged by the pin 15 and the shaft may then be mounted thereon so that the reduced portion 20 of the collar 19 extends into the surrounding shell of the connecting key 14. The rod 24 is then inserted through the shaft and screwed through the member 13 until it engages the bottom of the socket 10, so that further turning thereof will cause the socket 13 to rise until it lifts the key 14 and shaft to

the desired elevation. The set screw 16 may then be screwed tightly against the member 13 for securely locking the same, and the wing nut 38 may be screwed down on the rod 24 so as to rigidly clamp said shaft and key 14 to the member 13. It will be observed, therefore, that after the proper adjustment is made, the parts to be operated upon are firmly held in fixed position within the socket 10.

Before the parts are assembled and secured in place, as above described, the tool should be placed in position resting on the top of the socket 10, as shown in Figs. 2 and 3. Said tool comprises a body portion 27 having an annular opening 28 of substantially the same diameter as the interior of the socket 10, and is milled out for providing a laterally extending opening 29 in which the rollers 30 may be rotatably mounted. Extending from one end of the body portion 27, there is a handle 31; and from the other end thereof, there is a longitudinally extending recess in which the block 32 is slidably mounted, said block having a bifurcated end in which the roller 33 is rotatably mounted. The adjusting screw bolt 34 is adapted to be screwed in the end of the tool, so that its inner end abuts the end of the block 32 for forcing it inwardly. The screw bolt 34 is provided with a longitudinally extending handle 35 having in the end thereof a cross rod 36 for turning the same and forcing the roller 33 inwardly under pressure.

In operating the tool, assuming that it has been placed upon the socket 10 and the connecting key 14 and shaft 17 secured in position through the opening 28 therein, as above described, the handle 35 is turned by the rod 36 until the rollers 30 and 33 are forced about the periphery of the key 14 at three points under pressure. The position of the key 14 will have been previously adjusted by operating the rod 24 vertically until the annular groove 21 about the reduced portion 20 of the collar 19 is directly opposite the beading flange 37 of said rollers. After the rollers have been forced under pressure against the key 14, the handles 31 and 35 of the tool may be grasped and the tool turned slowly about the key

so that the beading flanges 37 will force the metal of the key 14 into the groove 21 about the entire circumference thereof.

The beading operation will thus be performed without removing the pinion 18, collar 23 or associated parts from the shaft 17, and the pressure applied by the rollers will be entirely sustained by the shaft or collar so that said shaft will not be, even in the slightest degree, bent out of alignment.

The invention claimed is:

1. In a device for attaching a member to a hollow shaft, the combination of a holding means for securing said shaft and attachment together, including a rod adapted to extend through said shaft and attachment, clamping members adapted to screw on the ends of said rod for clamping said shaft and attachment together, a mounting into which said rod and the clamping member on one end thereof are adapted to extend, means for locking said rod in said mounting, and a tool supported on said mounting and adapted to surround said rod so as to engage about said shaft and attachment therefor for rolling an attachment bead thereabout when rotated with respect to said mounting.

2. In a device for attaching a member to a hollow shaft, the combination of a means for holding said shaft and attachment in position with respect to each other including a rod adapted to extend through said hollow shaft and attachment, a clamping nut adapted to screw on one end of said rod, a recessed member through which the other end of said rod is adapted to screw, a mounting for receiving said member against which the end of said rod may abut, a pin in said member extending into said attachment for preventing the rotation thereof, means for locking said member and mounting rigidly together in adjustable position, and a tool rotatably supported on said mounting in position to surround said attachment and shaft for rolling an attaching bead thereabout at a given position fixed by the adjustment of said member.

In witness whereof, I have hereunto affixed my signature.

CHARLES R. BOWERS.
